UNITED STATES PATENT OFFICE.

HUGO ARNDT AND ALBERT NÜRNBERG, OF BERLIN, GERMANY.

APPARATUS FOR DISTRIBUTING COMPRESSED AIR FOR PURPOSES OF VENTILATION.

No. 922,236.

Specification of Letters Patent.

Patented May 18, 1909.

Application filed May 17, 1907. Serial No. 374,263.

To all whom it may concern:

Be it known that we, HUGO ARNDT, a subject of the Emperor of Germany, residing at 29 Elizabethüfer, Berlin, in the Empire of Germany, factory owner, and ALBERT NÜRNBERG, a subject of the Emperor of Germany, residing at 8 Chausséestrasse, Berlin, in the Empire of Germany, engineer, have invented certain new and useful Improvements 10 in Apparatus for Distributing Compressed Air for Purposes of Ventilation, of which the following is a specification.

This invention relates to apparatus for distributing compressed air for purposes of ventilation. It belongs to the known type of air distributing apparatus in connection with which the air flows out of a pipe in the form of a star, and the pipe is rotated through the reactive force of the outflowing gaseous 20 body.

According to the present invention the distributing arms are in the form of hollow vanes, which rotate around the same axis. The compressed air flowing out of these 25 vanes is projected into the room through the rapid rotation of the vanes but after passing out is further dispersed by the following vane.

The improved apparatus is illustrated in 30 the accompanying drawing, Figure 1 being a longitudinal section and Fig. 2 an elevation of the apparatus. Fig. 3 is a transverse section taken through one of the vanes or blades.

35 A hollow body 1 is rotatively seated on a suitably drilled cone 2, which is attached to the admission pipe for the compressed air. On to this hollow body 1 pieces of piping 3 are screwed or otherwise secured, which piping however can be rotated somewhat, so as to enable the hollow vanes 4 which are fixed thereon to be adjusted more or less obliquely to their axis of rotation. The vanes 4 are retained in the position given to them by means 40 of the jam-nuts 5. The vanes or blades are composed of two metal plates, which are fixed to the pieces of piping 3 and tightly soldered over the whole circumference with the exception of one place for example, as shown, 45 on the edge of the vane where indicated by

the numeral 6, where a slot is left open, in the same place on each vane, and out of which the compressed-air flows. The slot may be replaced by a row of holes. Two or more of such vanes or blades may be arranged on the 55 hollow-body 1. If now in the case of all the existing vanes 4 the compressed air passes out at 6, it exercises a reactive action, through which the vane-wheel thus constructed is caused to rotate. The distribution of the air is thus effected in the manner described above.

Having fully described our invention, what we claim and desire to secure by Letters Patent is:—

1. Apparatus for distributing compressed air by reaction comprising a conical body connected to the air admission pipe, conduits or ways in said conical body opening communication between the admission pipe and the 70 exterior of the cone, a hollow casing rotatively mounted on said cone, and hollow vanes or blades mounted on said casing and in open communication with its interior, said vanes having screw-threaded stems fitting 75 screw-tapped openings in said casing and being provided with jam nuts and outlet openings substantially as described and for the purpose stated.

2. Apparatus for distributing compressed 80 air by reaction comprising a conical body connected to the air admission pipe, conduits or ways in said conical body opening communication between the admission pipe and the exterior of the cone, a hollow casing rota- 85 tively mounted on said cone, and hollow vanes or blades mounted so as to be obliquely adjustable on said casing and in open communication with its interior and outlet openings in said vanes or blades substantially as de- 90 scribed and for the purpose stated.

In testimony whereof we have hereunto set our hands in presence of two subscribing witnesses this 2nd day of May 1907.

HUGO ARNDT.
ALBERT NÜRNBERG.
